United States Patent

Des. 238,084

Patented Dec. 16, 1975

238,084

CIGARETTE LIGHTER

Kenjiro Goto, 28-13, 5-chome, Setagaya-ku,
Sakurajosui, Tokyo, Japan

Filed Dec. 13, 1973, Ser. No. 424,480

Term of patent 14 years

Int. Cl. D27—05

U.S. Cl. D27—42

FIG. 1.

FIG. 2.

FIG. 3.

FIG. 4.

FIG. 5.

FIG. 6.

FIG. 1 is an oblique view of a cigarette lighter showing my new design looking from the front and one side thereof;

FIG. 2 is a front end elevational view thereof;

FIG. 3 is a side elevational view thereof;

FIG. 4 is a rear end elevational view thereof;

FIG. 5 is a top plan view thereof; and

FIG. 6 is a bottom view thereof.

I claim:

The ornamental design for a cigarette lighter, substantially as shown.
